YARN TENSION DEVICE

August K. Schoenenberg, Grantwood, N. J., assignee to Robert Reiner, Incorporated, Weehawken, N. J., a corporation of New Jersey

Application March 19, 1941, Serial No. 384,077

4 Claims. (Cl. 242—154)

This invention relates to a yarn tension device and refers more particularly to a yarn brake or yarn control which is used in various types of textile machines, for instance, for supporting yarns on their way from bobbins to the beam of a warping machine.

An object of the present invention is the provision of a yarn tension device which can be easily and conveniently adjusted to yarns of different sizes, and which will operate with the same efficiency with yarns of any normal size.

Another object is to provide a single yarn tension device which can be used satisfactorily for tensioning yarns of different sizes ranging from forty-five deniers to one-hundred deniers, and more.

A further object is the provision of a yarn tension device the pressure of which upon the yarn may be varied from zero to a maximum.

Other objects of the present invention will become apparent in the course of the following specification.

In accomplishing the objects of the present invention, it was found advisable to provide a yarn tension device having a pivoted member and an adjacent stationary member, each of these members being provided with a plurality of gripping elements cooperating to form a braking passage for the yarn, the pivoted member being provided with a weight support which may cooperate with a vibration-dampening dash-pot arrangement and which is located on both sides of the pivot of the pivoted member.

The center of gravity of the pivoted member is usually situated between its pivot and the stationary member, so that the gripping elements of the pivoted member have the tendency to swing toward the gripping elements of the stationary member. By utilizing a support having ends extending on both sides of the pivot and by applying weights to any one of these ends, the center of gravity of the pivoted member may be shifted either toward or away from the stationary member and, in an extreme case, it may be even placed in a vertical plane extending through the pivot. Thus, by hanging weights at different ends of the support, the amount of pressure exerted upon the yarn by the gripping elements of the pivoted member may be varied from zero to any desired maximum, and this makes it possible to utilize the same tension device for yarns of any size.

The invention will appear more clearly from the following detailed description when taken in connection with the accompanying drawing 55

showing, by way of example, a preferred embodiment of the inventive idea.

In the drawing:

Figure 1 is a top view of a yarn tension device constructed in accordance with the principles of the present invention.

Figure 2 is a front view of the tension device shown in Figure 1.

Figure 3 is a section along the lines 3—3 of Figure 1; and

Figure 4 is a fragmentary perspective view illustrating the weight support.

The yarn tension device shown in the drawing comprises a stationary member 5, a pivoted member 6 and a support 9. The support 9 may be made of metal, while the members 5 and 6 may be made of porcelain. The tension device is mounted upon a rod or holder 7 extending through a passage 8 provided in the support 9. A screw 10 is carried by an extension 11 constituting a part of the support 9. The screw 10 may project into the passage 8 and is used for holding the tension device firmly upon the rod 7.

The support 9 contains a cylindrical chamber 12 constituting a part of a dash pot 13 which includes a piston 14 reciprocable within the chamber 12 and carrying a piston rod 15.

A curved yarn guide 16 may be connected with the support 9 by a suitable layer 17. The passage 20 for the yarn, which is provided in the guide 16, has a wider inlet 18 and a narrower outlet 19. The yarn emerges out of the outlet 19 at right angles to its direction at the inlet 18, and is then led through openings 21 provided in the gripping elements 22 to 27 constituting a part of the stationary member 5.

As shown in Figures 1 and 3, each of the gripping elements 22 to 27 has the form of an arm provided with an opening 24 close to its outer end, all of the openings 24 extending in alignment with each other. A plate 28 which carries the gripping elements 22 to 27 and which may be integral therewith, is connected by a bolt 29 with a supporting plate 30 constituting a part of the support 9.

The plate 30 is provided with arms 31 and 32 serving as brackets or supports for the pivot bar 33 carrying the pivoted member 6.

The pivoted member 6 is provided with gripping elements 34 to 39 which are situated between the gripping elements 22 to 27 of the stationary member 5. As shown in Figure 3, each of the gripping elements 34 to 39 of the pivoted member 6 has the form of an upwardly directed hook provided with a curved surface 39, the po-

sition of which determines the operative free area of an opening 21. The gripping elements 34 to 38 are integral with a supporting body 40 which has a comparatively round portion 41 (Fig. 3) extending in the direction toward the 5 plate 28 of the stationary member 5.

The supporting body 40 of the pivoted member 6 is mounted upon the pivot bar 33. The heaviest portion 41 of the pivoted member 6 is situated between the pivot bar 33 and the plate 28 of the stationary member 5. Due to this position of the center of gravity of the pivoted member 6, the gripping elements 34 to 38 have the tendency to swing downwardly in a direction toward the plate 28. Thus the gripping elements 34 to 38 tend to reduce the free operative area of the openings 21 and to exert pressure upon a yarn extending through these openings.

The pivot bar 33 is so constructed that it can be conveniently used as a carrier or support of weights, through the use of which the pressure exerted by the gripping elements 34 to 38 upon the yarn may be varied from zero to a maximum. This is attained by extending the pivot bar 33 in the form of a hook 42 having an adjacent weight-supporting portion 43 (Fig. 4). A continuation of the pivot bar 33 is bent in the form of a rod 44 extending at right angles to the original direction of the pivot bar 33 and having a projecting end 45. The weight-supporting portion 43 is limited by the hook 42 and the projection 45.

The opposite end of the rod 44 is connected with the piston rod 45 of the dash-pot 13 and extends through a slot 47 formed in the support 9; it has the form of a weight-supporting hook 46.

The pivot bar 33 is provided, therefore, with two weight-supporting portions 43 and 46. The portion 46 is situated upon that side of the pivot or axis of the pivoted member 6, which is closer to the stationary member 5, while the portion 43 is situated upon the opposite side of the pivot (Fig. 3).

Therefore, a weight or weights 47 placed over the hook 46 will shift the center of gravity of the pivoted member 6 further toward the plate 28 and will increase the pressure of the gripping elements 34 to 38 upon the yarn extending through the openings 21. On the other hand, if the weight or weights 47 were removed from the hook 46, and a weight or weights 48 were placed over the hook 42 upon the weight-supporting portion 43, the center of gravity of the pivoted member 6 would be shifted in the opposite direction, namely, toward the pivot or the axis of rotation of the pivoted member 6, thereby diminishing the pressure of the gripping elements 34 to 38 upon the yarn. By placing a lighter weight 47 upon the hook 46 and a heavier weight 48 upon the weight-supporting portion 43 (Fig. 4), the pressure of the gripping elements 34 to 38 may be slightly decreased.

In general, it is apparent that by suitably selecting the weights 47 and 48, and by hanging them in different combinations upon the weight-supporting portions 43 and/or 46, the pressure of the gripping elements may be set at any desired quantity ranging from zero to a maximum, the value of which is determined solely by constructional limitations of the yarn tension device.

In actual practice, the operator will select the weights 47 and 48 and their position upon the weight-supporting portions 43 and/or 46 of the pivot bar 33 depending upon the size of the yarn passing through the yarn tension device. The

5 yarn is unwound from a bobbin (not shown) and enters the inlet 18 of the passage 20 provided in the guide 16. The direction of the yarn at the inlet 18 is at right angles to its direction at the outlet 19, so that the yarn is somewhat stretched in the guide 16 which is sufficiently long to prevent the balloon of the yarn from being entangled with the brake. The yarn emerging from the outlet 19 passes through the openings 21 of the gripping elements 22 to 27 and is tensioned by the gripping elements 34 to 38. As already stated, the pressure of the gripping elements 34 to 38 has been set in advance depending upon the size of the yarn and may vary from zero to any desired maximum. The oscillations of the pivoted member 6, resulting from the speed of movement of the yarn, are damped by the dash-pot 13. The yarn leaving the yarn tension device is warped on the beam of a warping or beaming machine (not shown).

It is apparent that the specific example shown above has been given by way of illustration and not by way of limitation and that the structures above described are subject to wide variation and modification without departing from the scope or intent of the invention, all of which variations and modifications are to be included within the scope of the present invention.

What is claimed is:

1. A yarn tension device, comprising, in combination, immovable gripping elements, an elongated pivot bar, a supporting body mounted upon said pivot bar and rotatable therewith, and swingable gripping elements carried by said supporting body and cooperating with said immovable gripping elements to form a braking passage for the yarn, said supporting body and said swingable elements constituting a pivoted member having a center of gravity normally situated between the pivot bar and the immovable gripping elements, so that it tends to swing said swingable gripping elements toward said immovable gripping elements and to exert pressure upon the yarn; said pivot bar having an extension portion extending on both sides thereof and constituting supports for weights varying the position of said center of gravity.

2. A yarn tension device, comprising, in combination, immovable gripping elements, an elongated rod constituting a pivot bar, a supporting body mounted upon said pivot bar and rotatable therewith, and swingable gripping elements carried by said supporting body and cooperating with said immovable gripping elements to form a braking passage for the yarn, said supporting body and said swingable elements constituting a pivoted member having a center of gravity normally situated between the pivot bar and the immovable gripping elements, so that it tends to swing said swingable gripping elements toward said immovable gripping elements and to exert pressure upon the yarn; said elongated pivot bar having a continuation forming two weight-supporting portions situated on opposite sides of the pivot bar for varying the position of said center of gravity.

3. A yarn tension device, comprising, in combination, immovable gripping elements, an elongated rod constituting a pivot bar, a supporting body mounted upon said pivot bar and rotatable therewith, and swingable gripping elements carried by said supporting body and cooperating with said immovable gripping elements to form a braking passage for the yarn, said supporting body and said swingable elements constituting a

pivoted member having a center of gravity normally situated between the pivot bar and the immovable gripping elements, so that it tends to swing said swingable gripping elements toward said immovable gripping elements and to exert pressure upon the yarn; said elongated pivot bar having a continuation comprising a hook, a rod extending at right angles to the pivot bar and having a projecting end, and a weight-supporting portion situated upon one side of the pivot bar and extending between said hook and said projecting end, the other end of said rod having the form of a weight-supporting hook extending upon the opposite side of the pivot bar.

4. A yarn tension device, comprising, in combination, a support having a dash-pot, a guide connected with said support and having a passage formed therein, said passage having an inlet and an outlet extending at right angles to each other, a stationary member connected with said support and having immovable gripping elements having openings formed therein for the yarn, said openings being in alignment with each other and adapted to receive the yarn emerging from said outlet, an elongated rod constituting a pivot bar, 25

5 a supporting body mounted upon said pivot and rotatable therewith, and swingable gripping elements carried by said supporting body and having surfaces situated in alignment with said openings and cooperating with said immovable gripping elements to form a braking passage for the yarn, said supporting body and said swingable elements constituting a pivoted member having a center of gravity normally situated between the pivot bar and the immovable gripping elements, so that it tends to swing said swingable gripping elements toward said immovable gripping elements and to exert pressure upon the yarn; said elongated pivot bar having a continuation comprising a hook, a rod extending at right angles to the pivot bar and having a projecting end, and a weight-supporting portion situated upon one side of the pivot bar and extending between said hook and said projecting end, the other end of said rod having the form of a weight-supporting hook extending upon the opposite side of the pivot bar, and connected with said dash-pot.
